UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,756, dated February 7, 1882.

Application filed January 12, 1882. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of, first, the large independent bouquets, A B, partially covering angular bars or Grecian work; secondly, the independent smaller bouquets C D, partially covering angular bars or Grecian work; and,

thirdly, a ground ornamented by aquatic plants and wild fowl.

I claim—

The design for a carpet, substantially as shown and described.

In testimony whereof I have signed my name to this specification, in the presence of two subscribing witnesses, this 10th day of January, 20 A. D. 1882.

THOMAS J. STEARNS.
